UNITED STATES PATENT OFFICE.

DANIEL D. McTAVISH, OF MONTREAL, QUEBEC, CANADA, ASSIGNOR TO CANADA CARBIDE COMPANY, LIMITED, OF MONTREAL, QUEBEC, CANADA, A CORPORATION.

DESIGN FOR A DRUM FOR CONTAINING MATERIAL.

47,191.

Specification for Design.

Patented Apr. 6, 1915.

Application filed December 5, 1914 Serial No. 875,734. Term of patent 7 years.

To all whom it may concern:

Be it known that I, DANIEL D. McTAVISH, a subject of the King of Great Britain, residing at Montreal, Province of Quebec, Dominion of Canada, have invented a new, original, and ornamental Design for Drums for Containing Material, of which the following is a specification, reference being had to the accompanying drawing, forming a part thereof.

Figure 1 is a side elevation of a drum for

containing material and showing my new design; and Fig. 2 is a transverse section thereof.

I claim:

The ornamental design for a drum for containing material, as shown.

DANIEL D. McTAVISH.

Witnesses:

STANLEY C. KING,
FRED J. BEAN.
